MOUNTING

Edward J. Mastney, Berwyn, and John H. Williams, Chicago, Ill., assignors to Oak Mfg. Co., a corporation of Illinois

Application April 28, 1941, Serial No. 390,712

3 Claims. (Cl. 248—20)

This invention relates to a mounting and particularly to a mounting which can be readily transformed from a rigid mounting to a spring mounting or vice versa. Many devices, as for example radios, phonographs, etc., are provided with a spring mounting during normal use thereof. During shipment of such devices, it is customary to render the spring mounting inoperative to prevent damage.

The mounting means heretofore provided have been rather difficult and inconvenient to operate upon for changing from shipping condition to a normal use condition. As a result, many purchasers of such devices have failed to change the mounting from its shipping condition. This results in noisy operation in the case of a radio and more or less erratic operation with a phonograph or changer mechanism.

This invention provides a simple mounting which may be naturally and easily adjusted from a shipping condition to a normal usable condition and vice versa.

In the drawing:

Figure 1 is a top view looking down upon a base board upon which is supported some device as a radio, phonograph or the like.

Fig. 2 is a detailed elevation of one mounting in a shipping position.

Fig. 3 is a view similar to Fig. 2 but showing the mounting in a normal usable position.

Fig. 4 is a bottom view of a mounting.

A base board 10 which may be part of a cabinet, stand, shelf or the like has disposed thereon a device 11 such as a radio chassis, phonograph, record changer for phonograph or any other device having similar mounting requirements. Device 11 is mounted on base board 10 by means of a plurality of mounting means 12.

Each mounting means 12 includes as part thereof a portion 13 of the device itself. This portion 13 may be the chassis pan of a radio, motor board of a phonograph or any suitable base plate carrying the parts of device 11. Portion 13 is dished down to provide a region 14 and a threaded sleeve 15 into which a bolt 16 having a head 17 and shank 18 is disposed. Portion 13 also has a part 20 bent down toward base board 10.

Baseboard 10 may have a countersinking 21 and aperture 22 in line with dished region 14. A coil spring 24 is disposed between base board 10 and portion 13 and sets in countersinking 21 and around dished region 14. Shank 18 of bolt 16 has a peripheral slot or groove 25 near the end thereof into which a spring clip 26 may be sprung. This clip may have any desired shape and need only be larger than the diameter of aperture 22.

It is clear that bolt 16 should be long enough

so that with clip 26 in position, the bolt length should be somewhat greater than the combined dimensions of the thickness of base board 10 and length of part 20. A shipping pad 28 of paper, wood, etc., may be disposed between base board 10 and part 20 and tightly clamped therebetween by turning bolt 16 to raise head 17 thereof above portion 13 until clip 26 engages the bottom face of base board 10. In this position, bolt head 17 is above portion 13 and presents rather an unsightly appearance. Coil spring 24 should be compressed in this position of the mounting. The user of the device may then turn screw 16 down until head 17 fits into dished region 14 to provide a finished appearance. This will drop clip 26 clear of baseboard 10 and permit coil spring 24 to expand. Shipping pad 28 may be removed and a spring floating mounting be left.

It is possible to obtain a rigid mounting by turning bolt 16 up so that coil spring 24 is tightly compressed.

The spring clip at the bolt end will remain in position in spite of vibration but may be readily pulled out to dismantle the mounting if desired.

If desired, the bolt may be reversed so that head 17 is below base board 10.

What is claimed is:

1. A mounting comprising a base board and 30 a device to be mounted thereon, said device having at least one mounting region, said region having a threaded aperture therethrough and said base board having an aligned aperture, a bolt threaded through said region aperture and extending freely into said base board aperture, a spring tending to separate said device and base board and normally forming a spring mounting, means at the base-board end of said bolt for limiting bolt travel from said board toward said 40 region, means at the mounting region end of said bolt for limiting bolt travel in the reverse direction, said bolt having a travel range greater than necessary for tightly clamping said board and region together whereby at one extreme bolt position said region and board are tightly clamped together and at the other extreme bolt position said region and board have sufficient play therebetween to permit said spring mounting to be operative.

2. The structure of claim 1 wherein said bolt extends beyond the base board and device.

3. The structure of claim 1 wherein said bolt extends beyond the base board and device and wherein the bolt has an enlarged head at one end and a spring clip at the other end as the travel limiting means.

EDWARD J. MASTNEY.
JOHN H. WILLIAMS.
